(57) **CLAIM**

The ornamental design for a motorcycle trunk keyhole trim, as shown and described.

DESCRIPTION

FIG. 1 is a front perspective view of the motorcycle trunk keyhole trim of the present invention.

FIG. 2 is a front side view thereof.

FIG. 3 is a rear side view thereof.

FIG. 4 is a top side view thereof.

FIG. 5 is a bottom side view thereof; and, FIG. 6 is a first end view thereof, the opposite end being a mirror image of the first end view.

All areas contained within the broken lines on the top surface, and the rear surface, of the motorcycle trunk keyhole trim shown in broken lines form no part of the claimed design. The outwardly-extending feature in FIGS. 4, 5, and 6 shown in broken lines form no part of the claimed design.
